UNITED STATES PATENT OFFICE.

ARTHUR G. HOERNER, OF DAYTON, OHIO.

IRONING-BOARD.

No. 852,787.

Specification of Letters Patent.

Patented May 7, 1907.

Application filed April 2, 1906. Serial No. 309,238.

To all whom it may concern:

Be it known that I, ARTHUR G. HOERNER, a citizen of the United States, residing at Dayton, in the county of Montgomery and State of Ohio, have invented certain new and useful Improvements in Ironing-Boards; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in ironing boards and has for its object to provide an ironing board which may be firmly supported in an operative position or folded and placed out of way while not in use.

Further objects of the invention consist in providing means for firmly locking the parts in contact with a table or other device to which it is attached when in use, to the end that the device is entirely free from vibrations during its operation, all as hereinafter more fully described and pointed out in the claims, reference being had to the accompanying drawings, of which—

Figure I, is a top plan view of my improved ironing board. Fig. II, is a similar view of the underside showing the same folded. Fig. III, is a side elevation partly in section showing the ironing board in an operative position. Fig. IV, is a detached view of one of the ratchet plates. Fig. V, is an enlarged detail of the upper end of the supporting leg, the upper portion thereof shown in section.

In a detail description of the invention, similar reference characters indicate corresponding parts.

The ironing board consists of a combination of two boards, to-wit—1 which is used for ironing garments generally, and 13 which is a smaller detachable board which is used for ironing smaller articles more particularly sleeves. The main ironing board 1 has upon its underside two parallel ribs 2 which are united thereto and extend a substantial distance throughout the length of said board 1. These ribs afford two functions, to-wit—they very materially strengthen the board throughout its length, and being enlarged at the head end of the board, they provide means for the attachment of other parts pres-

ently described. Near the head of the board 1 there is a cross rib 3 on the lower side of said board and forming a transverse rib which combines with the longitudinal ribs 2 to strengthen the board and prevent any perceptible warping thereof. The head of the board is provided with a rectangular opening 4 through which the head 6 of a leg 6' projects. This leg 6' when utilized supports the board 1 by engaging the upper edge of a table 5, while the extreme head end of the board 1 engages the lower side of the table as at 5'. The head of said leg 6' is cut out as at 8 in order that there may be sufficient clearance between said head and the edge of the table 5 to permit a proper contact between the parts. This contact is made at the point 7 which designates the extreme upper end of the leg 6' and is in the form of a nose which bears against the upper side of the table. This portion of the leg so engaging with the upper side of the table consists of a bifurcated member constructed of metal and having two parallel sides 16 which are joined to a base 21 which is united with the extreme end of the leg by means of a suitable number of screws 25. The upper portion of the base 21 terminates in a ratchet tooth 17, and the side plates 16 are joined by a transverse pin 15. This head permits of the attachment of the sleeve board 13 above and parallel with the ironing board 1; such attachment is made through means of a metallic member 14 which is secured to the under side of the sleeve board 13 and has a portion 18 projected therefrom on a proper angle to enter the head of the leg 6' between the sides 16. The projecting portion 18 has its extreme end 18' curved upwardly to engage the cross pin 15, and the under side of the part 18 is provided with ratchet teeth 18' which engage the tooth or projection 17 of the metallic base 21, and thus the said sleeve board 13 is supported in a position parallel with the ironing board 1.

The ironing board 1 is susceptible of adjustment in its position, as will be presently described, therefore, it is obvious that the sleeve board 13 must likewise be susceptible of adjustment; this is accomplished through the ratchets 17 and 18' as before described. The connection between the supporting leg 6' and the ironing board 1 consists of two plates 9 which are attached opposite to each other on the inner sides of the braces 2 just below the opening 4 in the head of the board.

1; these plates 9 have slots 12 which terminate in one side in ratchet recesses 11. Engaging these ratchet recesses are pins 10 which pass through and engage the upper portion of the 5 leg 6' and engages on each side said recesses 11.

It will be understood that the ironing board 1 may be supported on any one of the ratchet recesses throughout the length of the openings 12 and thus adjusted in its position 10 to that extent. This renders as before stated, the necessity of adjusting the sleeve-board 13. In order to afford a substantial support for the ironing board 1 throughout its length, free from vibrations, I provide a 15 brace co-operating with the leg 6' and consisting of a rectangular metallic frame which swings below the board 1 by being pivoted at 20 to the lower braces 2. The sides of this frame 19 extend on the outside of the leg 6' 20 and are provided with a series of internal ratchets 22 which are adapted to engage a pin 24 at any suitable point, said pin being extended through the body of the leg 6'. The upper portion of the openings forming 25 the ratchets 22, terminates in an extended slot 23' on each side which provides an entrance for the pin 24 when the parts are folded as in Fig. II.

I do not wish to limit myself to the adjustable features of the leg 6' as it is obvious the 30 pivot 10 might have a definite location in the side braces 2—2; for example, in cases where

the ironing board was used in connection with a table or other device of a definite height, it would not be necessary to adjust 35 the leg 6' in making the proper connections between said table and the ironing board, therefore, the pivotal connection between the leg 6' and the board 1 would be at a permanent point. 40

I claim:

An ironing board having an opening at one end, plates having internal ratchets attached to opposite sides of the longitudinal ribs of said ironing board, a supporting leg 45 having its upper end provided with a semi-circular recess adapted to be free from the engaging table at the extreme edge of said table, said supporting leg having a transverse pin adapted to lie within the internal 50 ratchets of the side plates, a swinging frame pivoted to said ironing board and inclosing the supporting leg, said swinging frame having internal ratchets, and a pin on said supporting leg engaging said internal ratchets 55 and whereby the ironing board is supported at a point adjacent to its center.

In testimony whereof I affix my signature, in presence of two witnesses.

ARTHUR G. HOERNER.
